CLAIM

The ornamental design for a front opening flat panel cabinet entertainment center, as shown and described.

DESCRIPTION

FIG. 1 is a front perspective view of a front opening flat panel cabinet entertainment center showing my new design; FIG. 2 is a perspective view comparable to FIG. 1 except on an enlarged-scale and with environmental matter removed; FIG. 3 is a front elevational view of FIG. 2; FIG. 4 is a right side elevational view of FIG. 2, the opposite side being a mirror image; FIG. 5 is a top plan view of FIG. 2; FIG. 6 is a bottom plan view of FIG. 2; FIG. 7 is a rear elevational view of FIG. 2; FIG. 8 is an elevation view taken in the direction of arrows VIII-VIII in FIG. 2, and partly in section; FIG. 9 is an elevation view taken in the direction of arrows IX-IX in FIG. 8, and partly in section; FIG. 10 is a perspective view comparable to FIG. 2 except on a reduced-scale and with the cabinet doors open as well as with the fold-up shelves folded out to horizontal; FIG. 11 is a front elevational view of FIG. 10; FIG. 12 is a right side elevational view of FIG. 10, the opposite side being a mirror image; FIG. 13 is a top plan view of FIG. 10; FIG. 14 is a bottom plan view of FIG. 10; FIG. 15 is a rear elevational view of FIG. 10; and, FIG. 16 is an elevation view taken in the direction of arrows XVI-XVI in FIG. 10, and partly in section. The broken lines in drawing represent environmental subject matter that forms no part of the claimed design.
